UNITED STATES PATENT OFFICE.

HENRY H. FORINGER, OF ERIE, PENNSYLVANIA.

DESIGN FOR A SUPPOSITORY.

SPECIFICATION forming part of Design No. 35,087, dated September 17, 1901.

Application filed February 4, 1901. Serial No. 45,801. Term of patent 7 years.

To all whom it may concern:

Be it known that I, HENRY H. FORINGER, a citizen of the United States, residing at No. 143 West Eighth street, in the city of Erie, in the county of Erie, State of Pennsylvania, have invented and produced a new and original Design for Suppositories, of which the following is a specification, reference being had to the accompanying drawings, forming part thereof.

Figure 1 is a view of the concave surface or upper side of my disk-shaped suppository. Fig. 2 is a view of the convex or lower surface of the same. Fig. 3 is a sectional view on lines $x x$, Figs. 1 and 2.

As shown in the drawings, the leading or material feature of my design consists of a solid disk having a concave upper face por-

tion B and a lower convex face portion D, the surrounding rim or peripheral edge portion of said concave and convex portions being enlarged or swelled, as shown at E C, and the central portion of the concave is provided with an integral cone or pyramid A, the upper end of which is flush or in a straight line with the rim or peripheral edge portion C of said concave portion.

Having described my invention, what I claim as new is—

The design for a suppository as herein shown and described.

HENRY H. FORINGER.
